US00D612732S

(12) **United States Design Patent**
Takata et al.

(10) **Patent No.:** **US D612,732 S**
(45) **Date of Patent:** ** *Mar. 30, 2010

(54) **CONTAINER**

(75) Inventors: **Carolyn Takata**, Laguna Niguel, CA (US); **Thomas Murphy**, Lake Mills, WI (US); **Todd L. Peseck**, Shawnee, KS (US)

D120,226 S 4/1940 Lundy
D120,587 S 5/1940 Hinkins

(73) Assignee: **Silgan Containers LLC**, Woodland Hills, CA (US)

FOREIGN PATENT DOCUMENTS

FR 2584680 1/1987

(*) Notice: This patent is subject to a terminal disclaimer.

DESCRIPTION

FIG. 1 is a top, perspective view of a container showing our new design;

FIG. 2 is a bottom perspective view thereof;

FIG. 3 is a front elevation view thereof, the left side, the right side and the rear elevation views being identical;

FIG. 4 is a top plan view thereof; and,

FIG. 5 is a bottom plan view thereof.

The ornamental design which is claimed is shown in solid lines in the drawings. The broken lines in the drawings are for illustrative purposes only and form no part of the claimed design.

1 Claim, 5 Drawing Sheets
